APPARATUS FOR USE IN THE MANUFACTURE OF PAPER

Karl Dammann, Trenton, N. J.

Application February 15, 1938, Serial No. 190,651

10 Claims. (Cl. 103—26)

My invention relates broadly to the manufacture of paper and more particularly to a control method and apparatus for varying the speed of centrifugal pumps for delivering paper pulp from a paper machine stock chest to the screen.

In processes of paper making, the expeditious and uniform handling of paper stock in the form of pulp has long been a problem, and imperfections in the finished products can be traced directly to variations in the handling of the pulp stock, particularly by pumps, and in the feeding of the pulp stock in the finishing steps. In the application of a centrifugal pump to the purpose of pumping paper pulp from a paper machine stock chest to the paper machine feed box, I have found that the quantity of discharge from the pump varies according to the height of the pulp stock in the machine stock chest and to changes in consistency or freeness, or both, in the pulp stock. By "consistency" is meant the absolute degree of density in the mass with regard to the proportions of solid fibre and vehicle; and by "freeness" is meant the relative firmness in the mass, or its degree of resistance under pressure and thus its inclination to flow through the pump.

I have also found that a controlled, variable speed, centrifugal stock pump is of the utmost importance in the manufacture of paper because the required head of delivery of the pump varies according to the consistency, freeness and sizing of the pulp stock. In order that a uniform product be obtained, a constant delivery of pulp to the paper machine is imperative, and therefore, a constant head, or pressure, over the machine feed gate in the head box must be maintained.

One of the objects of my invention, therefore, is to provide a control arrangement for the feeding of pulp stock to a paper making machine at uniform rate, regardless of its characteristics and of the amount of machine feed required.

Another object of my invention is to provide a construction of movable overflow gate controlled in accordance with the rate of delivery of stock for maintaining an approximately constant head of stock in the head box.

A further object of my invention is to provide a movable overflow gate in combination with means for controlling the speed of the delivery pump for maintaining a substantially constant head of stock in the head box.

Still another object of my invention is to provide a novel method of controlling the level of pulp stock in a head box fed by a centrifugal pump.

A still further object of my invention is to provide a method of controlling the level of pulp stock in a head box fed by a centrifugal pump involving a first, direct control of the level in accordance with the rate of delivery of stock to the box, and a second, indirect control of the level by control of the rate of delivery of stock by the centrifugal pump.

Still another object of my invention is to provide control means for regulating the speed of a centrifugal pump to maintain a constant level in a head box fed by the pump, the level being subject to change due to variation in the delivery of the pump accompanying variations in the characteristics of the stock.

A further object of my invention is to provide control means for regulating the speed of a centrifugal pump in combination with the control circuit of a driving electric motor, mechanically connected with the pump, whereby the pump is reduced to its lowest operating speed before stopping the driving motor.

Another object of my invention is to provide supporting means operative under shut-down conditions for relieving the actuating mechanism of my invention of undue pressure, and for maintaining the same in balanced condition.

Still another object of my invention is to provide an electrical control system for a centrifugal pump feed system in a paper making apparatus which is capable of functioning either in connection with an alternating current power supply system or a direct current power supply system.

Other and further objects of my invention reside in the systems and apparatus herein disclosed, and will be clearly understood by reference to the following specifications and to the accompanying drawings, in which:

Figure 1 is a diagrammatic showing of a general arrangement of apparatus for paper making and indicating the embodiment of my invention with respect to the machine-feed head box and the centrifugal pump feeding the same; Fig. 2 is a top plan view of the head box showing the control apparatus of my invention; Fig. 3 is a side elevation view of the head box shown in plan in Fig. 2; Fig. 3A is a detail view in elevation taken at the line 3A—3A in Fig. 3; Fig. 4 is an end elevation view of the head box, and shows the machine feed gate at the outlet from the box; Fig. 5 is a vertical sectional view of the head box taken at line 5—5 in Fig. 2 and showing particularly the action at the adjustable overflow gate of my invention; Fig. 6 is an elevation

view of the pilot valve structure with the valve chamber shown in section; Fig. 7 is a partial vertical sectional view thereof taken on line 7—7 in Fig. 6; Fig. 8 is a top plan view thereof, partially in section as at line 8—8 in Fig. 6; Fig. 9 is a horizontal sectional view through the valve chamber at line 9—9 in Fig. 7; Fig. 10 is a schematic diagram of the electrical connections in the control system of my invention as embodied in Fig. 1; Fig. 11 is a diagrammatic illustration of a modified control arrangement employing a variable speed, direct current, driving motor, instead of a variable speed transmission mechanism and a constant speed motor as indicated in Fig. 1; and Fig. 12 is a schematic diagram of the electrical connections in the modified control arrangement shown in Fig. 11.

In normal operation with a homogeneous stock, the discharge pressure or head, and the quantity of stock delivered will vary with the speed of a centrifugal pump; and by controlling the speed under a given discharge pressure the quantity of stock delivered may be regulated, or by controlling the speed with a constant quantity of stock demanded the discharge pressure may be regulated. When pumping paper pulp stock, however, or any similar pulp stock, it is found that the above stated conditions do not always obtain because the stock may not be homogeneous but may vary in consistency, freeness, and sizing, the latter referring to constituents of paper pulp stock which partially determine its quality. In such cases the discharge pressure of the centrifugal pump is subject to variation and for a given speed of operation the pump will accordingly deliver varying amounts of stock. In accordance with my invention, the speed of the pump is varied in accordance with the characteristics of the stock, as evidenced by variation in the delivery head, so that a substantially constant quantity of stock is delivered by the pump under a substantially constant head to the machine-feed head box.

In order that the pump may be run for the most part at an economical constant speed, I provide a primary control of the level of stock in the head box in the form of a movable overflow gate which permits a greater overflow as the rate of discharge of the pump increases and less overflow as the rate decreases, without affecting the speed of the pump. Any appreciative variation in the quantity discharged, and consequent variation of the level in the head box, operates the pump control system for increasing or decreasing the pump speed, as may be required. In this manner, a substantially constant head and uniform quantity of stock delivered are maintained, regardless of the characteristics of the pulp stock and of the amount of machine feed required, within the practical capacity of the pump.

Referring to the drawings in more detail, in Fig. 1 reference character 1 indicates the beater chest where the fibrous raw material is reduced to pulp, motor 2 being employed to drive beaters 3 and also a pump 4 for transferring the pulp stock to a jordan 5, driven by motor 6, wherein mixing is effected with desired bleaches, sizing materials and the like. The jordan delivers the stock to a machine chest 7 before its controlled delivery to the paper machine through the machine-feed head box 8. The box 8 is provided with an adjustable outlet or machine-feed gate 9 through which the pulp passes to a make-up waterbox 10 wherefrom it is pumped to the screen 11 and taken to the finishing machines.

From the chest 7 the pulp is drawn into centrifugal pump 12 and discharged through pipe 14 to the head box 8. An overflow gate 15 having a movable section 16 divides the head box 8 into two chambers; pipe 14 discharges into the filled chamber 8a, and the other chamber 8b constitutes an overflow chamber connected by return pipe 11 with the chest 7. The pump 12 as shown in Fig. 1 is driven by a constant speed motor 18 through a variable speed transmission at 19. Control motor 20 is connected with the variable speed transmission for regulating the operation thereof with respect to the motor 18 and pump 12. Motors 18 and 20 are controlled by the circuit means shown in Fig. 10, as will hereinafter be set forth in detail.

Referring now to Figs. 2-5 showing the structure of the head box 8, in more detail, means are provided for automatically controlling the movable gate section 16. A corrugated float 21 is mounted on lever arms 23 which are fixed to shaft 24 mounted in bearings 25 on the top edge of the box 8. The float 21 may be formed of corrugated sheet metal or molded material, in the form of a closed elongated body substantially cylindrical in outline, and may be fixedly or revolvably mounted in the lever arms 23. The corrugated wall makes the float structure rigid, and is easily maintained in clean condition for insuring the proper operation of the system.

The float 21 controls a pilot valve 26 through an adjustable lever arrangement which includes an arm 27 fixed to the shaft 24, an adjustable link 28, 29, and lever 30. The arm 27 is provided with a counter-weight 31 for the float assembly, and has a series of apertures 21a for selectively connecting with the yoke member 28 of the adjustable link. Lever 30 likewise is provided with a series of apertures, 30a, for selectively connecting with the bolt member 29 of the adjustable link. The leverage derived from float 21 may thus be determined, by connecting the link 28, 29, in selected apertures in arm 27 and lever 30. It will be noted that the shaft 24 and the pivot 30b, of lever 30, are arranged so that the leverage adjustment is facilitated and the adjustable link 28, 29, may be maintained substantially vertical, reference being had particularly to Fig. 3.

The pilot valve 26 is shown in more detail in Figs. 6-9, and comprises a cylindrical valve chamber 32 and a piston valve 34 which is connected with and controlled by lever 30 at 30c, as shown. The valve chamber 32 has a fluid pressure inlet 32a at the middle thereof, and an exhaust 32b at one end which communicates with the opposite end through duct 32c, Fig. 6. Valve 34 is a type of D valve forming a sealed chamber communicating with the pressure inlet 32a and normally in central position. When valve 34 is shifted upwardly by a rise of float 21, pressure is communicated from the inlet 32a to an outlet 32d connected with pipe 35, a second outlet pipe 36 and duct 32e being connected with the exhaust 32b at the same time. Alternatively, when valve 34 is shifted downwardly by a fall of float 21, duct 32d is opened to the exhaust 32b and pressure is communicated from the inlet 32a to the duct 32e and outlet pipe 36.

The normal central position of valve 34 for any desired position of float 21 is maintained by the adjustable link 28, 29, which as shown in Fig. 3A, comprises the yoke member 28 and bolt member 29. Adjustment is effected by means of nuts 29a on the bolt member 29, which may be set to clamp the yoke member 28 within a wide range of

adjustment. The valve 34 is biased in its central position by coil springs 37, the force of which may be regulated by nuts 38 on the axial supporting bolts 39. Bearing plates 40 are provided on opposite sides of the lever 30 to equalize the spring pressure. Pivot 30b is initially set by adjustment of bolt 41 by nuts 42 to establish the central position of the valve 34 with the desired bias of springs 37. The pilot valve 26 including the actuating lever 30 is mounted in a suitable framework on the outer wall of the head box 8, as indicated.

Referring again to Figs. 2-5, the movable gate section 16 is supported by links 43 from lever arms 15 45 fixed to shaft 46 which is mounted in bearings 47 on the upper edge of the head box 8 similarly to bearings 25 for shaft 24. An actuating lever 48, fixed to shaft 46 is connected through link 49 with the piston 50 of a hydraulic device 20 actuated by pressure controlled by the pilot valve 26. Outlet pipe 35 connects to cylinder 51 of the hydraulic device above the piston and pipe 36 connects below the piston. Accordingly, a rise of float 21 causes a differential of pressure in cylinder 51 with pressure greater in pipe 35 and on the top of the piston 50. Gate 16 therefore is moved to a lower position to permit a greater overflow of stock to reduce the head in the chamber 8a until it again stands at the desired level. Conversely a fall of float 21 causes the gate section 16 to be raised by effecting a differential of pressure in cylinder 51 greater on the lower side of the piston 50. In this connection, it may be noted that fall of the float may be due to the stopping of pump 12 in which case the system is shut down. Control being no longer required, it is desirable to relieve the apparatus of strain and accordingly I provide an arm 52 fixed to shaft 24 and arm 53 fixed to shaft 46 substantially in the relation shown in Fig. 3, and of such length that the ends thereof will overlap. When the pump 12 is stopped, the stock in box 8a recedes through the pump to the level in the machine chest 7, and thereby allows float 21 to fall to near its limit of movement. As the pilot valve 26 is actuated accordingly, piston 50 and gate section 16, rise, as above noted, and also arm 53, which meets the end of arm 52 and supports it as piston 50 continues to rise. Pilot valve 26 and float 21 are actuated through arm 52 and brought to and maintained in normal position. The entire control arrangement is now in a balanced condition. As soon as pump 12 is started again, the stock will slowly rise against float 21, and when float 21 is raised above its normal position pilot valve 26 is actuated, as has been described, and the regulator is again in operation.

The foregoing control arrangement constitutes the primary control of my invention and is operative independently within predetermined limits of variation in the stock level. Connected for parallel operation with piston 50, I provide an electric control switch 54 which is actuated from the piston by rod 56 rigidly connected with the piston by arm 57. Rod 56 is supported in guides 58, which are conveniently formed as extensions at the ends of cylinder 51, and has a lug 59 secured thereto for operation of the switch lever 60. The switch 54 is so constructed that limited movement of the lug 59 is permitted without operation of the switch contacts, the switch being maintained normally in open circuit condition and adapted to close either of two circuits as the lug 59 rises or drops beyond its free limits, as will be more fully set forth.

The control arrangement shown schematically in Fig. 10 is provided in combination with a two-phase, three wire, alternating current power supply and a constant speed, pump driving motor 18. The control system employs the control motor 20, an auxiliary source of power 61, and control switches and relays as shown. The motor 18 is adapted to be started through a switch system indicated generally at 62 which includes a multiple switch 63 for connecting the motor 10 to the power lines through resistors 64, 65, 66, and a multiple switch 67 for shunting the resistors as the motor gains speed. Overload relays 68 and 69 are provided in two of the lines to the motor 18 with their contacts in circuit 15 with the auxiliary power source 61 for disconnecting the control system and releasing the line switches 63 and 67.

It will be understood that three-phase alternating current, or any suitable supply circuit for the motor used at 18, may be provided in conjunction with the control circuit of my invention.

More particularly the control circuit of my invention includes a separate starting switch 70, 28 a main control switch 71, and the automatic control switch 54, connected with the source 61 for operating the motor 20 with respect to the motor 18 and the conditions of stock in the system. The switch 71 has two positions which may be termed "Stop" and "Run", one set, 72, of two contacts being closed in the former position while two sets, 73, and 74, of two contacts each are actuated in the latter position. With the main control switch 71 in "run" position, the starting switch 70 connects the actuating winding 75 of line switch 63 with the source 61 through line switch control contacts 67a, contacts 73 and conductor 76. Simultaneously, the actuating winding 78 of a slow acting relay is energized in shunt with the winding 75 and operates after a short interval to close contacts 79 to energize the actuating winding 80 of line switch 67. Meanwhile, the push-button starting switch 70 may be released, as holding contacts 63a are closed upon operation of winding 75 and maintain the circuit through windings 75 and 78 until operation of the slow acting relay. The control contacts 67a are opened and holding contacts 81 for relay 80 are closed upon actuation of the line switch 67, the relay windings 75 and 78 being deenergized at contact 67a, opening line switch 63 and contacts 79. Motor 18 is thus directly connected with the power lines and running at constant speed, subject to being disconnected by release of relay 80 controlling switch 67.

With switch 71 in "run" position, the source 61 is connected with one contact of each pair of contacts, 82, 83, in the automatic control switch 54 through contacts 73 and conductor 76. The other contact of the upper pair 82 in switch 54 connects through contacts 74 and limit switch 84 with one of the controlling terminals of reversible motor 20, the neutral terminal of which is connected back to the source 61. Thus, with switch arm 60 thrown upwardly to close contacts 82, motor 20 will drive in one direction, in this instance to alter the variable speed transmission 19 for driving the pump 12 at a greater speed. The limit switch 84 is controlled by the variable speed transmission 19, and opens within a range determined by the upward limit of the range of variation in the transmission 19.

The other contact of the lower pair 83 in 78

switch 54 connects through relay contacts 85 with the other controlling terminal of reversible motor 20, so that with switch arm 60 lowered to close contacts 83, motor 20 will drive in reverse direction to lower the speed of pump 12. The relay contacts 85—together with contacts 86 which are connected in shunt with contacts 73—are controlled by winding 87 energized by the source 61 through limit switch 89, which is closed in the normal operation of the system. Limit switch 89 like the switch 84, is controlled by the variable speed transmission 19, and opens within a range determined by the lower limit of the range of variation in the transmission 19; thus, the two switches, 84 and 89, cannot be open at the same time.

The automatic operation of switch 54 is therefore evident: decrease in the delivery of the pump, due to a stock of less freeness or of greater consistency, will result in operation of the pilot valve 26 to control the position of the movable gate section and to actuate switch 54, closing contacts 82, and resulting in a higher pump speed to increase the delivery of the pump; whereas, increase in the delivery as shown by a higher head of stock in the box 8 causes the reverse effect by closing contacts 83 which results in a decrease of the pump speed and, accordingly, a decrease in the delivery therefrom. In either event, the pump speed is maintained constant at a new rate which provides a substantially constant level of stock in the head box 8 under the conditions of adjustment.

When it is desired to cease operations, the main control switch 71 is thrown to "stop" position, relay 80 being held energized through contacts 86 until the motor 20 has set the variable speed transmission 19 for driving the pump 12 at the slowest speed. This is effected by means of the stop contacts 72 which are effectively in shunt with the contacts 83 on switch 54, and connect the motor 20 with the source 61 for regulating the transmission 19. In this connection, however, unlike that through contacts 83, there is no automatic opening of contacts 72 and the motor 20 runs until limit switch 89 is opened, which deenergizes winding 87, releasing contacts 85 in circuit with the motor 20, and contacts 86 in circuit with relay winding 80 which results in release of line switch 67. Motors 20 and 18 are thus stopped, and the only further action in the system is the operation of arm 53 to raise arm 52 and the float 21 to balanced condition, as described.

By virtue of the control arrangement for stopping as above described, the transmission 19 is conditioned so that motor 18 may be started under small load, with the pump 12 driven at its slowest speed and under a low head of stock. As contacts 82 on automatic switch 54 are usually closed under these conditions, the load is gradually increased automatically until normal operation is attained.

Similar results may be obtained in accordance with my invention by employing a variable speed driving motor directly connected with the pump 12, as indicated diagrammatically in Fig. 11. Either direct or alternating current variable speed motors may be employed, but in Fig. 12 I have preferably shown the control system of my invention in combination with a direct current variable speed motor with the control motor at 20' adapted to control the speed thereof for regulating the operation of the pump 12.

The control arrangement shown in Fig. 12, as well as the driving motor 90, derives its power

from the line source. The motor 90 is compound wound and includes armature 90a, series connected field 90b, and shunt connected field 90c. The starting system indicated generally at 91 includes a resistance 92 connected in the armature circuit to be progressively decreased in the starting operation. Speed control is effected by means of resistance at 93 in the shunt field circuit, the resistance being under the control of control motor 20'.

Motor 90 is started by operation of push-button switch 94, thus energizing relay windings 95 and 96 through the normally closed contacts of stop switch 97. Relays 95 and 96 are energized by line voltage through a shunt switch 98 but upon the operation of relay 95, delayed with respect to the operation of relay 96, switch 98 is opened and a resistor 99 is left in circuit with the relay windings to decrease the current therein. Operation of relay 95 is retarded by dashpot 100, or other suitable means, in order that the voltage on motor 90 will be progressively increased over a period of time. Resistor 92 is provided with a series of tap connections, 92a, adapted to be contacted in order by a shunt-connector 101 under control of the relay 95, for shunting the several sections of the resistor. One side of the power source is connected with the shunt-connector 101, which thus serves also as a line switch with respect to the shunt field 90c. It will be shown that the shunt field is always connected to the power supply at line voltage, for slowest speed in the motor 90 at the start. The shunt-connector 101 also connects with contact 103 to shunt the starting switch 94 and hold relays 95 and 96 energized. 35

Operation of relay 96 opens contacts 104 which are connected in shunt with contacts 83 on the automatic control switch 54, and closes contacts 105 which are in series with contacts 82 on switch 54. Motor 20' operates limit switches 84 and 89, similarly as motor 20 in Fig. 10.

In effect, the operation of the control system of Fig. 12 is substantially identical with that of the system of Fig. 10, the speed of pump 12 being controlled directly at motor 90, Fig. 11, rather than through the variable speed transmission 19, Fig. 1. Briefly, a lowering of stock in the head box 8 causes contacts 83 on switch 54 to close which completes the circuit to one of the controlling terminals of reversible motor 20' through contacts 105 and limit switch 84, motor 20' operating to increase the resistance in circuit at 93 which results in increase of speed at motor 90 and pump 12. Conversely, rising of stock in the head box will cause contacts 83 to close, completing the circuit to the other controlling terminal of reversible motor 20' through limit switch 89, motor 20' operating in reverse direction to decrease the resistance in circuit at 93 and lower the speed of motor 90 and pump 12. 60

Operation of motor 90 may be stopped by pressing button switch 97 which deenergizes relay windings 95 and 96. Motor 90 is immediately disconnected from the source at the shunt-connector 101, and the shunt at 103 on the starting switch 94 is removed. However, motor 20' is energized through contacts 104 and limit switch 89, and operates to set resistance 93 for the slowest speed of operation of motor 90, which is zero resistance in circuit, at which stage limit switch 89 opens 70 and disconnects motor 20'. Thus the condition of the system for starting is such that motor 90 and pump 12 will have the slowest speeds within the range of adjustment. As contacts 82 on switch 54 are usually closed under such condi-

tions, however, motor 20' will be promptly energized to increase the speed of motor 90 and pump 12 to normal, the progression from the start being even and without surges in speed such as would result in improper delivery of stock and unsatisfactory operation of the control system.

Similar control means may be provided in conjunction with a variable speed alternating current driving motor, or with any variable speed centrifugal pump driving arrangement, the control motor, as at 20 and 20', being adapted in all such arrangements to control mechanism affecting the speed of the pump 12.

Thus, while I have defined my invention in certain preferred embodiments, I desire it understood that modifications may be made therein, and that no limitations upon my invention are intended, except as are imposed by the scope of the appended claims.

What I claim as new and desire to secure by Letters Patent of the United States is as follows:

1. In a pumping system for supplying a uniform demand of pulp stock, a centrifugal pump, a head box having a partition for dividing said box into a head chamber connected with the discharge side of said pump and an overflow chamber connected with the intake side of said pump, a movable gate section forming an upward extension of said partition between said chambers, and means controlled by changes in the level of stock in said head chamber due to changes in the rate of delivery of stock caused by changes in the consistency and freeness of the pulp stock which affect the capacity of said pump for varying the position of said movable gate section for regulating the rate of overflow of stock thereover in accordance with variation in the head of stock on the discharge side of said pump resulting from said variations in the characteristics of the pulp stock.

2. In a pumping system, apparatus as set forth in claim 1 wherein said means for varying the position of the movable gate section comprises a float supported on the stock in said head chamber, a pilot valve controlled by said float, and hydraulic actuating means controlled by said pilot valve and connected with said gate section.

3. In a pumping system, a head box having a head chamber and an overflow chamber, a movable overflow gate section between said chambers, a float mounted by lever arms in said head chamber and adapted to be supported by the stock in said chamber, means controlled by said float and connected with said gate section and operable to vary the position of the movable gate section above and below a normal position as the level of stock falls and rises, respectively, an arm connected with the said lever arms, and means connected with said gate section and engageable with said arm with the gate section substantially displaced above its normal position corresponding to a low position of said float under shut down conditions for raising said float out of contact with the residual stock in said head chamber.

4. In a pumping system, a head box having a head chamber and an overflow chamber, a movable overflow gate section between said chambers, a float adapted to be supported on the stock in said head chamber, a pilot valve controlled by said float, hydraulic actuating means connected with said movable gate section and controlled by said pilot valve for varying the position of said gate section above and below a normal position in accordance with fall and rise, respectively, in the head of stock in said head chamber, and an

adjustable connection between said float and said pilot valve for determining the normal position of said gate section relative to said float for maintaining the level of stock at the desired head.

5. In a pumping system for supplying a uniform demand of pulp stock, a centrifugal pump adapted for use with pulp stock, a head box connected with the discharge side of said pump, a return duct from said head box to the intake side of said pump, means controlled by limited changes in the level of stock in said head box due to variations in the rate of delivery of stock for varying the rate of return of stock from the discharge to the intake of said pump through said duct, and means controlled by excessive changes in the level of stock in said head box due to variations in the rate of delivery of stock for regulating the speed of said pump and thereby the rate of delivery of stock from said pump in counteraction of said variations in the rate of delivery, said variations in the rate of delivery of stock by said centrifugal pump being due to variations in the consistency and freeness of the pulp stock affecting the capacity of said centrifugal pump, the last said means including an electric control system having a two-position switch mechanically connected with the aforesaid means for varying the rate of return of stock and actuated in conjunction therewith, and electric circuit means controlled by said switch and operative to effect variation in the speed of said pump for altering the rate of delivery therefrom.

6. In a pumping system, apparatus as set forth in claim 5 and including in said means for regulating the speed of said pump a constant speed motor for driving said pump and a variable speed transmission between said motor and said pump; said electric circuit means including a reversible motor connected with said transmission for varying its operation with respect to said pump, and accordingly the speed of the pump.

7. In a pumping system, apparatus as set forth in claim 5 and including in said means for regulating the speed of said pump a variable speed motor for driving said pump, and a separate speed control element for said motor; said electric circuit means including a reversible motor connected with said element for varying its operation with respect to said motor and accordingly the speed of said motor and said pump.

8. In a pumping system, apparatus as set forth in claim 5 and including in said electric circuit means, switch contacts connected in shunt with the contacts in a selected position of said two-position switch and operable under shutting-down conditions in said system for actuating said electric circuit means for effecting low speed driving conditions with respect to said pump.

9. In a pumping system, apparatus as set forth in claim 5 and including in said means for regulating the speed of said pump a constant speed motor for driving said pump and a variable speed transmission between said motor and said pump; said electric circuit means including a reversible motor connected with said transmission for varying its operation with respect to said pump, and accordingly the speed of the pump, and switch contacts connected in shunt with the contacts in a selected position of said two-position switch and operable under shutting-down conditions in said system for energizing said reversible motor for adjusting said transmission to slowest driving relation for restarting.

10. In a pumping system, apparatus as set forth in claim 5 and including in said means for regu-

6
lating the speed of said pump a variable speed motor for driving said pump, and a separate speed control element for said motor; said electric circuit means including a reversible motor connected with said element for varying its operation with respect to said motor and accordingly the speed of said motor and said pump, and switch contacts

connected in shunt with the contacts in a selected position of said two-position switch and operable under shutting-down conditions in said system for energizing said reversible motor for adjusting said speed control element for slowest speed operation of said motor upon restarting.

KARL DAMMANN.
